CLAIM

The ornamental design for a ceiling fan blade iron, as shown and described.

DESCRIPTION

FIG. 1 is a bottom perspective view of a ceiling fan blade iron showing my new design in use;

FIG. 2 is an enlarged bottom perspective view of the ceiling fan blade iron in accordance with my design;

FIG. 3 is an enlarged bottom plan view of the ceiling fan blade iron in accordance with my design;

FIG. 4 is an enlarged top plan view of the ceiling fan blade iron in accordance with my design;

FIG. 5 is an enlarged side elevation view of the ceiling fan blade iron in accordance with my design;

FIG. 6 is an enlarged opposite side elevation view of the ceiling fan blade iron in accordance with my design;

FIG. 7 is an enlarged back elevation view of the ceiling fan blade iron in accordance with my design; and,

FIG. 8 is an enlarged front elevation view of the ceiling fan blade iron in accordance with my design.

The broken line showing of the ceiling fan, the fan blade iron attachment members and the apertures is included for the purpose of illustrating environmental structure and forms no part of the claimed design.
